CLOTHESPIN

James N. Howard, R.R. 2, Box 279, Edwardsburg, Mich.

Continuation of design application Ser. No. 67,330, Nov. 1, 1961. This application Mar. 14, 1963, Ser. No. 74,029

Term of patent 3½ years

(Cl. D17—6)

FIG. 1

FIG. 3

FIG. 5

FIG. 6

This is a continuation of my copending application Serial No. D. 67,330, filed November 1, 1961, and now abandoned.

I claim:

The ornamental design for a clothespin, substantially as shown and described.
